UNITED STATES PATENT OFFICE.

MAX GURSKY, OF BROOKLYN, NEW YORK.

CHAIR BED.

Application filed September 22, 1924. Serial No. 738,977.

This invention relates to a new and improved chair bed.

One of the objects of my invention is to provide a chair which can also be used as a bed.

Another object of my invention is to provide a chair whose front and back can be simultaneously adjusted, so that the said front and back can be held in a variety of positions.

Another object of my invention is to provide a simultaneous adjustment for the front and back of a chair, so that when the back is tilted backward the front is tilted forward.

Another object of my invention is to provide a device of this character, having a minimum number of parts, which can be connected in an efficient and simple manner.

Another object of my invention is to provide a device of this character, which shall be efficient, easy to operate, and which will not get out of order.

Other objects of my invention will be set forth in the following description and drawings, which illustrate, a preferred embodiment thereof.

Fig. 1 is a perspective view showing the back and the front of the chair in the vertical position.

Fig. 2 is a perspective view showing the back and the front of the chair tilted, and also showing a mattress which can be placed upon the bed.

Fig. 3 is a perspective view showing the front and the back of the chair tilted as much as is possible, while keeping it in the form of a chair.

Fig. 4 is an elevation, and shows the connection between the front and the back of the chair.

Fig. 5 shows the device used as a bed.

Fig. 6 shows the operating parts in the position in which the device is used as a bed.

As clearly shown in Fig. 1 and in Fig. 3, the device has a seat portion 7, which is held upon back legs L and upon front legs 17.

The front and rear legs of the chair are connected by braces 19. Additional braces are provided at the upper corners of the chair. The seat portion 7 of the chair, as well as the other parts thereof, may be provided with springs 2, of any suitable type.

The front legs 17 of the chair are connected by braces 9 and 10, and additional

braces 11 and 12 may be also provided, as clearly shown in Fig. 1.

The front 27 of the chair may be provided with end brace 8.

As clearly shown in Fig. 3, the back 1 of the chair is provided with braces 3 and 4, which are not directly connected to the back of the chair, but are connected to a rear frame having legs 5, as clearly shown in Fig. 3. The legs 5 are connected at 24 to bars 25, which are pivotally connected at 26 to the legs L. Hence, the legs 5 always remain vertical, no matter how much the back 1 may be tilted. One of the bars 25 is provided with a projection P, and a lever 22 which is pivoted at 23 to one of the legs L, has a series of ratchet teeth, which are adapted to engage the projection P, so that when the lever 22 is turned by means of a knob H, the back of the chair may be tilted and then held in a number of different positions.

As can be seen in Fig. 2, the construction of the control mechanism is of the simplest description because it consists merely of a single lever 22 directly pivoted to one of the rear legs of the chair. The ratchet shape of the teeth prevents any downward movement of the bars 25 when the projection P on one of said bars 25 is engaged by one of the said ratchet recesses. Each front leg 17 and each rear leg L consists substantially of an angle bar having inner lateral faces. That is, the lateral transverse faces of the said angle bars extend towards each other so that the members connecting the front and rear of the chair are located within the structure of the chair. This enables the bar 22 to be pivoted on the outer side of one of the rear legs L. Hence, if the entire device is covered by a suitable decorative covering, which is customary, there are no moving parts which can possibly engage this covering, save the control lever 22, whose movement is so slight that it will not engage the ornamental covering.

A spring 40 shown in Fig. 4 pulls the lever 22 so that it will engage the projections P. There may be two of such levers 22, but only one of them is shown in the drawing.

The bars 25 have links 36 pivotally connected thereto, and these links 36 project through slots S in the legs L. The links 36 are pivotally connected at 35 to levers 34,

which are pivoted at 33 to the bars 19. The levers 34 are connected to links 18, and these are connected to the front 27 of the chair at the pivots 31'. The links 18 pass through slots S in the front legs 17 of the chair.

Hence, when the back of the chair is tilted, the front of the chair is also tilted forward at the same time, so that the chair may be 10 placed in the various positions shown in the drawings, in which it can serve as an easy chair or as a bed.

The mattress C may be of any suitable type, and the device can be covered in any 15 suitable manner so as to conceal the framework.

It will be noted as seen in Fig. 1, that the spring 40 is centrally located, and that its lower end is connected to the pivoted frame 20 50, which is connected to the lever 22.

It will be noted that all the connections between the front and back of the chair, pass internally between the legs of the chair, so that when the back is tilted, the covering of 25 the chair is not caught by any moving parts. In addition, the slots S firmly guide the said connections, so as to stiffen the device against any lateral strains, and the lever 22 is relieved from any such lateral strains.

I have described a preferred embodiment

of my invention, but it is clear that numerous changes and omissions could be made without departing from its spirit.

I claim:

In a chair, the combination of a seat supported upon a pair of front legs and a pair of rear legs, each said leg comprising an angle iron having a vertical slot therein, braces connecting each rear leg to the corresponding front leg, levers pivotally mounted upon the said braces, a pair of front links passing through the slots in the front legs and pivotally connected to the lower parts of the said levers and to a chair front pivotally connected to the said seat, 45 a chair back having a third pair of legs pivotally connected thereto, a third pair of links pivotally connected to the third pair of legs and to said rear legs, rear links pivotally connected to the upper ends of the said 50 levers and to the third pair of links, one of said three pair of links having a projection, and a control lever pivotally connected to one of the rear legs and having a series of ratchet recesses adapted to engage the said 55 projection.

In testimony whereof I hereunto affix my signature.

MAX GURSKY.
